Primary Examiner — Jonathan J Han*Assistant Examiner* — Jennylou M Binas(74) *Attorney, Agent, or Firm* — Erik J. Overberger; RANKIN, HILL & CLARK LLP(57) **CLAIM**

The ornamental design for a drain cleaner as shown and described.

DESCRIPTION

FIG. 1 is a top front perspective view of an embodiment of a drain cleaner.

FIG. 2 is a rear view of the drain cleaner of FIG. 1.

FIG. 3 is a front view of the drain cleaner of FIG. 1.

FIG. 4 is a left side view of the drain cleaner of FIG. 1.

FIG. 5 is a right side view of the drain cleaner of FIG. 1.

FIG. 6 is a top view of the drain cleaner of FIG. 1; and,

FIG. 7 is a bottom view of the drain cleaner of FIG. 1.

The broken lines shown in the figures are for the purpose of illustrating portions of the drain cleaner that form no part of the claimed design.
